DESIGN FOR A FOLDING KNEE MIRROR

Paul D. MacWilliams, Los Angeles, Calif., assignor, by mesne assignments, to Louis M. Neubeiser and Wanda E. Neubeiser, both of Glendale, Calif.

Application February 21, 1948, Serial No. 144,663

Term of patent 14 years

(Cl. D86—2)

To all whom it may concern:

Be it known that I, Paul D. MacWilliams, a citizen of the United States, residing at Los Angeles, in the county of Los Angeles and State of California, have invented a new, original, and ornamental Design for Folding Knee Mirror, of which the following is a specification, reference being had to the accompanying drawing, forming part thereof.

Fig. 1 is a plan view of a folding knee mirror, showing my new design.

Fig. 2 is a perspective view with the mirror folded in position to set on a flat surface.

Fig. 3 is a side view in elevation of the mirror folded in position to set on a flat surface.

Fig. 4 is a perspective view of the mirror in position to fit on the knee of a user.

I claim:

The ornamental design for a folding knee mirror, substantially as shown and described.

PAUL D. MACWILLIAMS.
